US0D1112163S

(12) **United States Design Patent** (10) **Patent No.:** **US D1,112,163 S**
(45) **Date of Patent:** **** Feb. 10, 2026**

(54) **EARPHONE**

(71) **Applicant:** **Anker Innovations Technology Co., Ltd.**, Changsha (CN)

(72) **Inventors:** **Hangyu Li**, Shenzhen (CN); **Zheng Wei**, Shenzhen (CN)

(73) **Assignee:** **Anker Innovations Technology Co., Ltd.**, Changsha (CN)

(**) **Term:** **15 Years**

(21) **Appl. No.:** **29/928,022**

(22) **Filed:** **Feb. 7, 2024**

(30) **Foreign Application Priority Data**

Aug. 7, 2023 (CN) 202330499138.0

(51) **LOC (15) Cl.** **14-01**

(52) **U.S. Cl.**

USPC **D14/223**

(57) **CLAIM**

The ornamental design for an earphone as shown and described.

DESCRIPTION

FIG. 1 is a front perspective view of an earphone showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines depict portions of the earphone that form no part of the claimed design.

1 Claim, 8 Drawing Sheets
